Diagram of a plow share with dimensions 14, 17, 16, and 18. The share is shown with a vertical line and a diagonal line. The vertical line is labeled 14 at the top and 17 at the bottom. The diagonal line is labeled 16 at the top and 18 at the bottom. To the right of the share, there is handwritten text: "Inventor Charles Bindhamer", "Jones Bain Cook", and "Attys:".

UNITED STATES PATENT OFFICE.

CHARLES A. BINDHAMMER, OF CHICAGO, ILLINOIS.

ANNUNCIATOR.

1,381,180.

Specification of Letters Patent. Patented Feb. 17, 1920.

Application filed January 2, 1918. Serial No. 209,980.

To all whom it may concern:

Be it known that I, CHARLES A. BINDHAMMER, a citizen of the United States, residing at Chicago, in the county of Cook and

5 State of Illinois, have invented certain new and useful Improvements in Annunciators, of which the following is a specification.

10 My invention relates to improvements in apparatus for holding and consecutively displaying cards that may bear upon their faces subject matter for advertising purposes.

15 One of the objects of my invention is to provide a device for holding a series of display cards and means for consecutively displaying said cards, by means, or through the instrumentality of means, operable from a remote point.

20 Other and further objects of my invention will become readily apparent, to persons skilled in the art, from a consideration of the following description when taken in conjunction with the drawings, wherein:—

25 Figure 1 is a front elevation of the device as it will appear to announce a series of acts at a theater.

Fig. 2 is a front elevation of the card-holding mechanism.

Fig. 3 is a side elevation of the same.

30 Fig. 4 is a detail of the escapement arm. In all the views the same reference characters are employed to indicate similar parts.

35 The apparatus is designed to hold a series of announcing cards, arranged in consecutive order, to be exposed, one after another, in regular sequence to give notice to a theatrical audience of the change of acts and the name or designation of the act being performed.

40 The apparatus is preferably contained behind the proscenium arch of the stage, and the cards are displayed, at intervals, through a suitable opening made in the vertical wall of the arch.

45 There are usually two devices and corresponding sets of cards to be displayed, one at each side of the arch. Heretofore an employee changes the card in one set, and walks across the stage, before the audience, and changes the card of the other set.

50 In the contemplated use of my device the cards of the two sets may be simultaneously changed, by closing an electric circuit from a remote point. The point for closing the circuit may be located anywhere on the stage, 55 out of sight of the audience so that it will

not be necessary for the manipulator of the device to expose himself to the view of the audience.

The simplest form that my invention may 60 take is illustrated in the accompanying drawings, wherein 5 is an inclined support comprising a rod for holding the card, fixed at one end, as at 6, to a vertical upright 7. Each of the cards 8 is secured to a hook 9 65 and supported on the rod 5. An electro-magnet 10 is suitably fixed to a stationary part of the structure, and is provided with an armature or arm 11, which is responsive to the magnet. The arm 11 is pivoted, as at 12, 70 and is normally held in retracted position, as shown in Fig. 2, by a spring 13. The lower end of the armature or pivoted arm 11 is provided with an escapement plate 14 secured to the arm in any suitable way, as 75 by screws 15. The escapement plate 14 is bifurcated on its lower end and is somewhat wider at its upper end, and is provided with two separated blades 16 and 17. The blades preferably have chisel edges 18 80 which confront each other, for a purpose to be more specifically referred to. They are displaced rearwardly and forwardly of each other substantially equal to the thickness of said hangers.

85 The electro-magnet 10 is energized by a battery 20, when the circuit is closed by the key or button 21 over the wires 22, 23 and 24.

Normally the spring 13 holds the prong 16 of the escapement plate 14, in contact 90 with the surface of the rod 5, thereby serving as an abutment for retaining the hooks 9 on the rod. When the circuit is closed, the armature is attracted,—as shown in dotted lines in Fig. 2,—causing the prong 16 to 95 move up into contact with the rod 5 and permitting the adjacent hook 9 to drop off, by effect of gravity, from the end of the rod. The prong 17 will retain the remaining number of hooks in place on the rod 5 until 100 the magnet is deenergized, whereupon the prong 16 will be instantly returned to its normal position by the spring 13 and prevent other hooks than the one liberated by the single impulse, from leaving support on 105 the rods 5. Each time the circuit is closed a single card will be dropped in the manner described.

110 It will be manifest to one skilled in the art, that another device, substantially as that shown in the drawings, may be connected in parallel with the one as illustrated

in Fig. 2, and when the circuit is closed by the button, or switch 21, both the devices will operate in the manner described, and each will drop a card in response to each 5 impulse of electric current that passes through the electro-magnets.

It will be manifest that the device herein disclosed may be used for other purposes than that described, as the invention is not 10 limited to the use, but pertains to the combination of features defined by the appended claims.

While I have herein shown a single embodiment of my invention for the purpose 15 of clear disclosure, it is manifest that changes may be made in the general arrangement and disposition of the parts within the scope of the appended claims.

Having described my invention, what I 20 claim is:—

1. In a device of the character described, the combination with an inclined elongated card support; a series of cards to be carried thereby; a hanger for each card providing 25 an eye threaded on the support; an escape-
ment comprising a lever pivoted to move in a plane bisecting the axis of the support and a plate secured to a free end of the lever, having two separated blades, one on each

side of the support, and displaced rear- 30 wardly and forwardly of each other sub-stantially equal to the thickness of one of said hangers and means to hold one of said blades normally in contact with said sup-
port.

2. In a device of the character described, a rod to support a series of cards inclined to an extent that said cards will drop there-
from by force of gravity when not resisted; 40 a hanger for each card having an eye on its free end whereby to thread the cards on said rod; an escapement to oppose movement of more than one card at a time, comprising a pivoted lever movable at substantially right angles to the axis of the rod; a plate on the 45 free end of said lever having two separated blades, one on each side of the rod, and dis-
placed with respect to the path of their movement an extent substantially equal to the thickness of one of said hangers; a 50 spring to hold one of said blades normally in contact with the rod and means to move the other blade into substantial contact with the rod, against the operation of the spring, to drop one card at a time from the rod. 55

In testimony whereof I hereunto set my hand.

CHARLES A. BINDHAMMER.
